PRESTRESSING MEANS FOR SLAB
CASTING FORMS

Theodore W. Shoe, Troy, Ohio, assignor to The Flexicore
Co., Inc., Dayton, Ohio, a corporation of New York
Filed May 17, 1963, Ser. No. 281,312
1 Claim. (Cl. 249—94)

This invention relates to prestressing means for slab casting forms and more particularly for slabs of the type disclosed in United States Patent No. 2,299,111, and the like. Slabs of this character are cast in long forms and are frequently provided with prestressing strands or wires extending the length of the slab for the purpose of imparting desired structural and stress characteristics. While slabs of this character may range anywhere from about 16 feet in length and up, the casting forms for such slabs are generally of the order 40 or 50 feet in length to provide for the maximum slab lengths to be cast.

Where a long casting form is used and where the slab to be cast does not utilize the maximum length of the casting form, it is clear that means must be provided for determining the length of a slab during the casting operation. In the patent referred to, this means assume the simple form of having the sides of the casting form provided with regularly spaced apertures to determine the longitudinal position of one bulkhead. The bulkhead, which in this case would be the dead bulkhead, would be anchored in position by pins extending through the apertures in the casting form sides. In order to prevent the sides of the casting from showing the location of such casting form apertures, it is necessary to provide plugs for filling these apertures. Even then, the side of a casting is not perfectly smooth.

Another means for accomplishing the above involves the use of bulkheads at the two ends of the casting form with an additional bulkhead disposed intermediate the ends of the casting form to form a mud stop which cooperates with one end bulkhead to determine the actual length of a casting. This involves wasting considerable length of prestressing wire extending between the mud stop bulkhead and the end bulkhead beyond the casting region.

This invention relates to a bulkhead structure which can be used with casting forms having solid sides but can be positioned at any desired point along the length of a form without wasting prestressing strands or requiring any change in the structure of a casting form.

Prestressing strands are tensioned to a substantial degree. A bulkhead which supports at least three and possibly five or six strands tensioned to a substantial amount results in an overall force on the bulkhead which is quite high and requires means for reinforcing the bulkhead and the casting form against collapse. This invention provides a bulkhead structure which may be positioned at any desired position along a casting form and which position may be changed easily and which involves a minimum loss of prestressing strand, while at the same time not interfering with the design of the casting forms. The invention involves a bulkhead structure having means for directing the forces created by the tensioning of the strands in such a way that the normal casting form structure can withstand the forces without in any way interfering with the normal function of the casting form.

In order that the invention may be understood, it will now be disclosed in connection with the drawings wherein:

FIGURE 1 is a top plan view of a casting form equipped with the new prestressing means.

FIGURE 2 is a side elevation of the structure illustrated in FIGURE 1, with certain parts broken away.

FIGURE 3 is an end view on line 3—3 of FIGURE 1.

FIGURE 4 is an enlarged section on line 4—4 of FIGURE 1.

FIGURE 5 is a view along line 5—5 of FIGURE 1.
FIGURE 6 is a view along line 6—6 of FIGURE 1.

FIGURE 7 is a perspective detail of the stressing bar forming part of the invention.

5 The casting form to which this invention may be applied may be any one of a number of structures. Thus the casting form may be similar to the ones illustrated in the patent previously referred to or, preferably, may follow the teachings of United States Patents Nos. 3,023,476 and 10 3,023,477 disclosing one-piece casting forms whose sides are adapted to be bent outwardly and whose bottoms are adapted to be buckled inwardly to release castings. Thus the casting form may consist of flat bottom 10 having sides 11 and 12. Sides 11 and 12 extend upwardly toward top 15 edges 13 and 14 of the casting form. The top portion of each casting form side is shaped to provide keys in the casting. Parts 15 and 16 of the casting form are specifically shaped along the lines shown to provide a keyway. Whether the casting form side is solid or merely has the 20 interior surface thereof shaped to provide the keyway is not important.

The casting form includes channels 18 and 19 rigidly secured to the outside faces of sides 11 and 12 of the casting form. Channels 18 and 19 have top and bottom 25 flanges 20 to 23 inclusive, these flanges extending outwardly away from the sides of the casting form. Top flanges 20 and 22 of the channels are provided with apertures 25 and 26 disposed at regular intervals along the 30 length of the flanges. Except for apertures 25 and 26, the casting form so far described is disclosed in Patents Nos. 3,023,476 and 3,023,477 previously referred to.

The casting form has one end, here illustrated as the left end of FIGURE 1, as the front end of the casting form. The front end of the casting form has rigidly attached thereto flat end bulkhead 28 having overhanging flange 29 extending away from the casting region. As 35 illustrated in the drawings, the casting form is adapted to have five laterally spaced prestressing strands extending along the length of the casting near the bottom thereof for prestressing the casting. Bulkhead 28 is the live bulkhead in that the tension of each of the prestressing strands can be adjusted to a desired value.

At each prestressing strand position there is provided 40 threaded nut and bolt means, generally indicated by 30, and including strand chuck 31 and pulling T 32. A jack or other means for exerting tension on the prestressing strand is coupled to T 32 and strand 33 is tensioned to a suitable degree, assuming that the other end of strand 33 is retained by means to be described. In tensioning strand 50 33, elongation will occur. The threaded take-up means, generally indicated by 30, permits the elongation of the strand to be taken up so that when the tension on pulling T 32 is released, strand 33 will have its tension maintained. The means for establishing and maintaining tension on a 55 prestressing strand is more fully disclosed and claimed in the copending application of Nieber et al., Serial No. 86,689, filed February 2, 1961. It is understood that other means for establishing and maintaining tension on a wire strand may be utilized.

60 The means for maintaining the strand tension at the dead bulkhead generally consists of two parts which may be combined into one if desired. However, the parts are more conveniently maintained separately with a saving in weight and making the entire bulkhead structure 65 much less cumbersome and easier to handle.

Insofar as function is concerned, the dead bulkhead combination comprises strand deflecting bulkhead generally indicated by 40 and stressing bar assembly generally indicated by 41. Referring first to the strand deflecting bulkhead, this comprises dead bulkhead 45 having suitable strand clearance openings 46. Dead bulkhead 45 is shaped and dimensioned so that it lies within the cast-

ing form and conforms to the shape of sides 11 and 12 of the casting form. Dead bulkhead 45 is rigidly secured to top plate 48 which is long enough so that ends 49 and 50 thereof overlie top flanges 20 and 22 of the casting form side channels. Ends 49 and 50 of top plate 48 are provided with a number of spaced apertures for accommodating bolts 51 and 52. By spacing apertures 25 and 26 on the one hand at one distance and apertures in ends 49 and 50 on the other hand at a different distance, it is possible to utilize the difference in spacing for obtaining a fine adjustment of positioning top plate 48 along the length of the casting form. Thus as an example, by having apertures 25 and 26 spaced along three-inch centers and having the apertures in ends 49 and 50 of top plate 48 spaced along two-inch centers, it is possible for bolts 51 and 52 to be used along one inch intervals. Bolts 51 and 52 have nuts so that top plate 48 can be securely bolted to top flanges 20 and 22 of the channels. Spacers 54 carried by top plate 48 are disposed between the top flanges of the channel and top plate 48 to take up any separation between the two.

Rigidly secured to the bottom of top plate 48 and to the inside or rear face of dead bulkhead 45 are U-shaped strand deflecting members 60 positioned to register with the lateral position of each prestressing strand 33. Each strand deflecting member 60 has bottom convex curved edge 61 shaped as illustrated in FIGURE 4 to guide strand 33 from its normal position near the bottom of the casting form upwardly at an angle toward the top of the casting form. Strand deflecting member 60 is as thick as the diameter of heaviest strand 33 used. A strand presses against the rear portion of curved edge 61 of the deflecting member.

To prevent strand 33 from slipping laterally from the edge of a strand deflecting member, retaining plates 63 and 64 are rigidly secured to the bottom part of a strand deflecting member. These retaining plates extend beyond curved edge 61 and cooperate therewith to form a U-shaped slot for retaining prestressing strand 33 against slipping laterally off. The particular shape of deflecting member 60 is not important and the particular shape of curved edge portion 61 is not important except that the portion of edge 61 remote from dead bulkhead 45 should slope upwardly in a smooth curve.

The angle at which strand 33 is deflected toward the top of the casting form determines the stress in bolts 51 and 52 and also the moment to be resisted by the strand deflection assembly. For best results, it is desirable that the resultant of force created at edge 61 by tensioned strand 33 tending to raise the strand deflecting assembly upwardly should intersect the bottom face of top plate 48 in a vertical plane defined by the center line extending between the two center apertures in ends 49 and 50, assuming three apertures at each end as illustrated. This resultant is shown in dotted lines in FIGURE 4. This arrangement is on the assumption that bolts 51 and 52 pass through the center aperture at ends 49 and 50. However, it is contemplated that bolts 51 and 52 can be used with either of the remaining two apertures at both ends of plate 48. If such is the case, then there will be a moment which will be the product of the resultant from edge 61 multiplied by the arm which will be the distance from the center of the aperture containing the bolt to the resultant force. This is illustrated in FIGURE 4 by resultant *a* and moment arm *b*, assuming that bolts 51 and 52 are offset to the right as viewed in FIGURES 1 and 4. If the bolts are offset to the left, the resultant will be the same except for algebraic sign (assuming that the aperture spacing is the same).

To dispose the strand deflecting assembly in position, it will have to be moved in from the open end of a casting form and threaded into position so that key forming portions 15 and 16 are properly engaged, after

which the strand deflecting bulkhead may be moved forwardly toward live bulkhead 28 to any desired position. Stressing bar assembly 41 includes crossbar 68 extending transversely across the top of the casting form and having anchor end portions 69 and 70. Each anchor end portion is provided with aperture 71 for accommodating bolts 72 which will pass through registering apertures in top flanges 22 and 20 of the side reinforcing channels.

Crossbar 68 has upwardly extending blocks 74 laterally spaced along the length of cross bar portion 68 and adapted to be in vertical registration with respective prestressing strands 33. Crossbar 68 and reinforcing blocks 74 together carry cross end plate 76 having aperture 77. These apertures are below crossbar portion 68 and register with reinforcing blocks 74 and accommodate the prestressing strands. Strand chucks 79 are disposed over the ends of the strands projecting through aperture 77 of cross end plate 76. Strand chucks 79, when the strands are tensioned, will press against cross end plate 76 with the full force of the tension in strand 33. Thus it will be understood that the construction of the entire stressing bar assembly must be sufficiently strong to withstand the tremendous force exerted thereon as a result of the tensions in all strands. In practice, waste strand between strand chucks 79 and the dead bulkhead can be kept down to no more than about three feet.

By having separate strand deflecting means and stress resisting means, the parts can be made relatively light and designed to resist their respective loads. Thus strand deflecting assembly 40 is subjected to a force component from strands 33 which tends to raise it above the casting form. The bolts for holding the strand deflecting assembly down against the top flanges of the casting form are the only parts in tension and can be selected heavy enough to be adequate.

Similarly, stress bar assembly 41 must be strong enough to resist the force tending to pull the same toward assembly 40 and also strong enough to resist the bending force due to the strand tension forces.

As a result, each part, strand deflecting and stress bar, can be designed for utmost efficiency to resist the loading involved. The reduction in weight and increase in strength make the parts easier to handle and less expensive to make.

By proper design, the center line of each strand 33 extending upwardly toward stress bar assembly 41 can intersect the line extending between the center lines of apertures 71 at the level of the top faces of the casting form top flanges. This will create a substantially pure shear force on bolts 72.

While dead bulkhead 45 has been illustrated as part of the strand deflecting assembly, it may be separated therefrom. In such case, ends 49 and 50 require only one bolt aperture each. The dead bulkhead is lightly loaded and can be adjusted to any desired location from the strand deflecting assembly by means of spacer blocks. Also one stress bar assembly has been illustrated for all strands in a slab. Where wide slabs are being made or if many strands are used, it is possible to have two stress bar assemblies, laterally offset along the length of the casting form. One stress bar assembly could accommodate certain strands and the other stress bar assembly could accommodate the remainder.

What is claimed is:

In combination, means for providing a casting region of adjustable length for prestressed slabs in a casting form having a maximum length of about 40 feet, said casting form being of steel having a generally U-shaped section with the sides reenforced by steel channels on the outside thereof extending the length of said form, each channel having a flange adjacent the top edge of the form side with the flange extending outwardly away from the form, the flanges having regularly spaced apertures therethrough, at least one bulkhead assembly

for mounting along a desired region along the length of said casting form, said assembly being capable of handling the total load of a plurality of tensioned steel strands with a minimum of waste of excess length of steel strand, said assembly comprising two sub-assemblies, one sub-assembly being a strand deflecting sub-assembly and the other being a strand stress bar sub-assembly, said strand deflecting sub-assembly comprising a generally flat steel plate extending across the casting form and being long enough to overlie the top flanges of the casting form channels, said plate having apertures therethrough for registration with the channel flange apertures, bolts for anchoring said steel plate in desired position along the top of said casting form, a dead bulkhead supported from said plate and extending into the casting form to define the end of a casting region, said dead bulkhead having apertures therethrough for accommodating prestressing strands, strand deflecting guides depending from the plate and extending from the outer face of said dead bulkhead and provided with guide slots for guiding the tensioned strands upwardly from the bottom of the casting form while retaining said strands in their normal positions laterally of the form sides so that looking down upon a casting form in normal casting position all strands appear straight, said stress bar sub-assembly comprising a bar extending across said casting form and having its ends overlying said apertured channel flanges, the cross bar ends being apertured to register with the channel flange apertures, bolts for anchoring said cross bar in desired position along the casting form, said stress bar sub-assembly being anchored at a region beyond the dead

bulkhead and outside of the casting region, a cross end plate rigidly secured to said cross bar and having apertures therethrough for said tensioned strands, said bar apertures being about level with the casting form edges and being aligned with the strand guide slots to permit strands to continue straight as seen in plan, said cross end plate and cross bar together providing a structural angle less than 90°, said stress bar sub-assembly being oriented so that the cross end plate will receive the upwardly guided strands substantially normal thereto when spaced a predetermined short distance from the strand deflecting sub-assembly, said cross end plate having an outer face remote from the strand deflecting sub-assembly for accommodating strand chucks to seat against said outer face, the strand length from the dead bulkhead to the chucks being waste.
